FIG. 4.

FIG. 5.

FIG. 2.

UNITED STATES PATENT OFFICE

2,555,847

WINDOW CURTAIN

Maurice Druck, Long Beach, N. Y.

Application December 16, 1948, Serial No. 65,700

2 Claims. (Cl. 160—348)

1

This invention relates to an improved curtain and, more especially, to ruffled, border-type curtains having a central top panel and a pair of depending, resiliently extensible side panels.

It is a primary object of the invention to provide a border-type curtain which may be readily hung from a supporting rod and which is provided with a pair of depending stretchable side panels adjustable for a wide variety of window sizes without requiring measuring, cutting and stitching.

Another object of the invention is the provision of a curtain of the character indicated wherein the stretchable side panels are formed into gathers or shirring throughout the length thereof by means of longitudinally extending elastic threads stitched to the back surface of the side panels in unobtrusive position.

A further object of the invention is the provision of a curtain of the character indicated which is adjustable to a wide variety of window sizes; which is designed in such a manner as to be positively supported from its top central panel without sagging; which is provided with resiliently shirred side panels related in such a manner to the top support panel thereof as to provide a continuously ruffled and attractive appearance when hung from a curtain rod; and which may be fabricated easily and inexpensively.

The foregoing objects as well as additional objects and advantages of the invention will be readily apparent in the course of the following detailed description taken in connection with the accompanying drawing which illustrates a preferred embodiment of the invention, and wherein:

Fig. 1 is an elevational view of a curtain embodying the features of the invention hung in place about a window;

Fig. 2 is an enlarged detailed front view of a portion of one of the depending side panels of the curtain;

Fig. 3 is a fragmentary rear view of the curtain showing a curtain rod partially inserted within the retaining pocket of the central panel, a portion of the central panel being gathered upon the rod to provide a ruffled appearance continuous with the ruffles of the adjacent side panel;

Fig. 4 is a sectional view taken along line 4—4 of Fig. 3 illustrating the manner of securing the elastic threads to the rear of the side panel and the disposition of the decorative medial front band along which the shirring or gathering of each panel is formed; and

Fig. 5 is a sectional view taken along line 5—5 of Fig. 3 illustrating the formation of a retaining pocket for a curtain rod on the top central panel of the curtain.

2

Referring now to the drawings in greater detail, the curtain is of the border-type and may be cut from any suitable material to form a central top panel 10 and a pair of depending side panels 11. Each of the side panels 11 is preferably provided with a medial front stiffening band 12 and with a pair of elastic threads 13 of rubber or the like extending longitudinally of the side panel on the rear side thereof and disposed on either side of said medial front band. Lines of stitching 14 secure the elastic threads 13 to the side panel, as shown in Fig. 4, and the innermost pair of said lines of stitching also serve to secure the front band 12 to the side panel 11. The elastic threads 13 are stitched to the side panel 11 in tensioned condition and the stitching 14 is relatively loose so that after the stitching operation has been completed said elastic threads will contract to form shirring or gathers along the medial band 12 and ruffles 15 at the terminal edges of the panel 11.

In order to provide positive support for the curtain, the top panel 10 is provided with a retaining pocket 16 for the insertion of a curtain rod 17, as shown in Fig. 3. The retaining pocket 16 may be conveniently formed by securing a medial band 18 to the front of top panel 10 by means of parallel marginal lines 30 of stitching 19 resulting in a pocket open at both ends for the reception of the curtain rod 17. Each side panel 11 may be joined to the top central panel 10 by means of a transverse line of stitching 20 interrupted to leave the ends 35 of retaining pocket 16 open.

In actual use the curtain is hung from and positively supported without sagging by means of the curtain rod 17 inserted within the retaining pocket 16. The stretchable side panels 11 are then extended to the desired length depending upon the size of the window about which they are being hung and the lower ends thereof are secured by means of tacks 21 or any other suitable fastening elements, as shown in Fig. 1. Ruffles 22 may be formed in the inelastic top panel 10 by gathering said top panel along curtain rod 17 and said top panel ruffles combine with the ruffles 15 of the stretchable side panels 11 to produce a continuously ruffled appearance 50 around the inner and outer marginal edges of the curtain.

The practice of the present invention thus provides a border-type curtain readily adaptable for windows of varying sizes and shapes which 55 may be positively supported without sagging from the top central panel and which is provided with resiliently, shirred, ruffled side panels conveniently extensible to any desired length along the window frame. The elastic threads 13 which 60 form the side panel ruffles 15 are further disposed

unobtrusively on the rear side of the side panels to contribute to a neat, attractive and esthetic appearance. Further, the design of the curtain involves an advantageous disposition of the ruffled, stretchable side panels 11 with respect to the central support panel 10 so that the curtain presents a continuous, uninterrupted ruffled appearance when hung in place.

Since certain modifications may be made in the curtain of the present invention without departing from the scope thereof, it is intended that all matter contained in the foregoing specification and shown in the accompanying drawing be interpreted merely as illustrative and not in a limiting sense.

What is claimed is:

1. A border-type curtain comprising a central supporting panel having a retaining pocket for the reception of a curtain rod and a pair of resiliently extensible side panels depending from said supporting panel, each of said side panels having a medial longitudinal stiffening band secured to the front surface thereof and elastic threads extending medially and longitudinally along the rear surface of each of said side panels on either side of said medial band, whereby to define a central, resiliently Shirred portion along said medial band and outer ruffled portions at the marginal edge of said side panel.

2. A border-type curtain comprising a central

10
15

supporting panel having a retaining pocket for

the reception of a curtain rod and a pair of resiliently extensible side panels depending from said supporting panel, each of said side panels having a medial longitudinal stiffening band along the front surface thereof, elastic threads extending medially and longitudinally along the rear surface of each of said side panels on either side of said medial band, whereby to define a central, resiliently Shirred portion along said medial band and outer ruffled portions at the marginal edges of said side panel, and lines of stitching securing said elastic threads to said side panel, some of said lines of stitching serving additionally to secure said medial stiffening band to said side panel.
